FREDERIC A. PARKHURST, OF BETHESDA, MARYLAND, ASSIGNOR, BY MESNE ASSIGNMENTS, TO PRO-PHY-LAC-TIC BRUSH COMPANY, OF WILMINGTON, DELAWARE, A CORPORATION OF DELAWARE

METHOD OF MAKING TOOTHBRUSH HANDLES

Application filed August 2, 1929. Serial No. 383,074.

This invention relates to a method of making tooth brush handles and the general object of the invention is to reduce the expense of making such handles.

5 Heretofore it has been the general practice to make tooth brush handles by cutting rectangular blanks in predetermined size and shape from a sheet of material, molding the blank in a die press to form a handle of proper size and shape and then finishing and 10 polishing the handle manually. In this method the rectangular blank was of necessity larger than the finished handle and the excess material was forced out between the 15 edges of the die forming a fin or flash. These fins or flashes were around the outside edges of the handles and had to be removed by hand methods as it was not practical to do the work by machine. The method described 20 involved a large number of steps and was slow and caused waste because of the loss of material contained in the large fins or flashes amounting to from 10 to 15 per cent and also because of the expense of removing 25 the fins and finishing the blank.

The object of my invention, therefore, is to provide an economical and practical method of making tooth brush handles which will avoid the difficulties and causes of expense already mentioned.

I accomplish this result by molding a large number of tooth brush handles in gangs or groups, the handles being on edge so that the fin or flash which connects each handle 35 with the next handle in the group is connected to the middle of the back or front face i. e. the large face of the blank and not to the edge. In practicing my method and 40 after the molding of each group of handles is completed the handles are readily separated from each other by the fingers, by reason of the fact that the fin or flash connecting them is very small and exceedingly 45 thin, thus permitted of readily buffing or otherwise removing what remains of the fin or flash from the two flat faces of each blank. This can be done cheaply and economically by passing the blanks through suitable automatic buffing machines.

Other objects of the invention will appear from the following description and appended claims when taken in connection with the accompanying drawings, in which

Fig. 1 is a perspective view of a blank of 55 pyroxylin or similar material.

Fig. 2 is a perspective view of a gang die with a gang of molded handles therein.

Fig. 3 is a perspective view of the molded 60 gang of handles.

Fig. 4 is a section through several of the handles, illustrating one method of separating the handles.

Fig. 5 is a perspective view of a separated 65 handle showing the fin or flash on one face thereof, the flash being of exaggerated thickness.

Fig. 6 is a perspective view of a finished handle.

Before explaining in detail the present invention, it is to be understood that the invention is not limited in its application to the details of construction and arrangement of parts illustrated in the accompanying drawings, since the invention is capable of other 70 embodiments and of being practised or carried out in various ways. Also it is to be understood that the phraseology or terminology employed herein is for the purpose of description and not of limitation, and it is not 75 intended to limit the invention beyond the terms of the several claims hereto appended as considered in view of the prior art and the requirements thereof.

In accordance with my method, I employ, 80 preferably, a sheet or slab of either partly seasoned or fully seasoned pyroxylin material, such as the slab 10, Fig. 1. The slab may be warmed on a steam table or elsewhere and placed in the slab forming die which 85 comprises upper and lower die members 11 and 12 respectively and is provided with a series of mold cavities corresponding in shape to the handles to be formed, these being arranged with their flat faces toward 90 each other. The die is so constructed that the flash or fin i. e. the portion of waste stock is exceedingly thin. In practice this is hardly thicker than tissue paper, but sufficient to hold the blanks together in a gang or cake. 95

The die is put into an hydraulic press and the slab therein is formed into a group or gang of molded tooth brush handles, as shown at 13 in Fig. 3. It will be seen from Figs. 3, 5 4 and 5 that the handles are positioned on edge and that they are interconnected by webs 14 called "flash". The next operation is to separate the individual handles of the group 13, which is done, preferably, by a 10 slight pressure of the fingers. After separation of the handles by the fingers, it will be seen that each handle is provided on opposite flat faces with an exceedingly thin fin or flash 16. By having the fins or flashes on 15 opposite flat faces of the handle rather than surrounding the edges of the handle, the fin or flash can be removed by a mechanical ashing or buffing device, after which a mechanical polisher may be employed to give the 20 handle a highly polished finish. This can be done only with difficulty if at all where the flash is on the edge of the blank. Then if desired the handles may be carried through a lacquer dip and humid drying chamber, or 25 the handles may be spread automatically on a foraminous work support and sprayed with lacquer. The finished handle is shown in Fig. 6.

I claim:

- 30 1. The herein-described method of making tooth brush handles which consists in molding a blank of pyroxylin material in a gang die to provide a gang or group of handles on edge with a fin connecting the middle of the 35 adjacent faces of adjacent handles, separating the individual handles, and thereafter removing the fins.
2. The herein-described method of making tooth brush handles in gangs or groups, 40 which consists in molding a slab of pyroxylin to form a group of handles on edge connected by fins at the middle of the adjacent faces, separating the individual handles, and removing the fins.
- 45 3. The method of making tooth brush handles which consists in molding a plurality of blanks in a die, said blanks being connected by a thin flash or fin joining the blank on the flat sides of the blank, and then separating 50 the blanks and removing the flash.
4. The method of making tooth brush handles which consists in molding a plurality of blanks in a die, said blanks being connected by a flash or fin joining the flat sides of proximate blanks, said fin being thin enough to permit the blanks to be readily broken apart without injury, separating the blanks and removing the traces of the flash.

In testimony whereof I affix my signature.

60 FREDERIC A. PARKHURST.
